UNITED STATES PATENT OFFICE.

EDWARD DONALD CAMPBELL, OF GALT, ONTARIO, CANADA, ASSIGNOR OF ONE-HALF
TO JAMES ALEXANDER WILKIE, OF GALT, ONTARIO, CANADA.

BARBER'S APPLIANCE.

1,413,515.

Specification of Letters Patent. Patented Apr. 18, 1922.

Application filed October 12, 1920. Serial No. 416,475.

To all whom it may concern:

Be it known that I, EDWARD DONALD CAMPBELL, a subject of the King of Great Britain, and a resident of the town of Galt, 5 in the county of Waterloo, in the Province of Ontario, Canada, have invented certain new and useful Improvements in Barbers' Appliances, of which the following is the specification.

10 My invention relates to improvements in barbers' appliances and the object of the invention is to devise an electrically driven instrument that will actuate hair cutting clippers in any position. A further object 15 is to provide means for connecting a vibrator to such instrument, and a still further object is to devise means for connecting a drying fan thereto.

20 My invention consists of the parts constructed and arranged, all as hereinafter more particularly described and illustrated in the accompanying drawing in which:

25 Fig. 1 represents an elevational view partly in section showing my instrument and the means for operating the clipper mechanism.

Fig. 2 is an elevational view of the removable casing shown in section in Fig. 1.

30 Fig. 3 is a horizontal section through the same.

Fig. 4 is an elevational detail showing the bayonet joint locking device for detachably securing the casing to the electric motor.

35 Fig. 5 is a vertical section showing the removable casing having the drying fan connected thereto.

Fig. 6 is a vertical section showing the vibrator attachment connected to the removable casing.

40 Fig. 7 is a plan view showing the clipping attachment, the casing being in section.

Fig. 8 is an enlarged vertical section through the casing showing the clipper attachment applied thereto.

45 Fig. 9 is a detail in plan of the upper movable knife of the clippers.

Fig. 10 is a similar detail of the lower fixed knife of the clippers.

50 Fig. 11 is a sectional detail through the knife operating means.

Fig. 12 is a plan view thereof, and

Fig. 13 is an enlarged vertical section of the vibrator attachment shown in Fig. 6.

Like characters of reference indicate cor- 55 responding parts in the different views.

1 is the electric motor provided with a

suitable handle 2. 3 is a depending portion through which the shaft 4 of the motor extends. 5 are stud bolts on the side of the depending portion 3. 6 is a wedge-shaped 60 male connecting member on the lower end of the motor shaft 4. 7 is a detachable casing having the bottom 8 and the aperture 9 in the side face thereof. 10 are vertical slots extending down from the upper 65 edge of such casing and connecting with the horizontal slots 11, said stud bolts 5 adapted to be inserted into the vertical slots upon the attachment of the casing to the depending portion 3 and such casing turned when 70 the bolts are at the bottom of the slot 10 so as to bring them into the horizontal slots 11, thus securing the casing to the depending portion 3 of the motor. 12 is a horizontal partition extending across the casing 75 7 and provided with depending legs 13 adapted to abut the interior of the casing and secured thereto by the screws 14. 15 is a vertical stub shaft extending through the partition 12 and mounted in a suitable bearing 16 therein, the upper end being provided with a tapered female connecting member adapted to receive the male member 6.

18 is a crank wheel secured to the lower 85 end of the shaft 15 by the key 19 and carrying the crank pin 20 which pivotally connects the clipper driving link 21 to the crank wheel for the purpose which will 90 hereinafter appear.

The above casing has been described as adapted for use with the clipper mechanism. When it is desired to use it with the drier fan it is constructed without any bottom 8, and the vertical shaft 15 is of greater length. 95 In this instance a fan casing 22 is provided having the nozzle 23 and the air inlet holes 24. 25 is a fan connected to the stub shaft 15.

When the casing is used in connection 100 with the vibrator the bottom 8 of such casing has a depending cylindrical member 26 formed thereon, said cylindrical member being open to the casing. The stub shaft 15 is in this instance provided with an eccentric foot 27. 28 is a rod extending vertically through the member 26 and having the enlarged hollow boss 29 formed at the top thereof into which the foot 27 on the shaft 15 extends.

110 The lower end 30 of the rod 28 is enlarged and has a cross aperture 31 extend-

ing therethrough, through which a lateral pin 32 extends, the diameter of the pin 32 being less than the diameter of the orifice 31. 33 is the vibrator sphere having a screw 34 threaded into the bottom of the lower ends 30 of the rod 28. 35 is a cap threaded onto the lower end of the member 26, said cap being provided with a central orifice 36 through which the lower portion of the end 30 extends.

10 I will now describe my clipper mechanism. 37 is a plate attached to the bottom 8 of the casing 7 by the screw bolts 38, said plate having a depressed foot 39. 40 is a lower knife of the clipper secured to the foot 39 of the plate 37 by the screws 41 which extend through holes 42 in such knife. 43 is a central indenture in the upper face of the knife 40 permitting the head 44 of the vertical bolt 45 to be inserted therein. 46 are a plurality of cross channels or slots in the upper face of the lower knife 40.

47 is the upper knife having the notch 48 at the centre of its rear face. 49 is the clipper operating arm having the hollow boss 50 through which the bolt 45 extends. 51 is a downwardly turned foot on the arm 49 adapted to be inserted into the notch 48 in the upper knife 47, the link 21 being 25 pivotally connected to the upwardly turned portion 52 of such arm 49. 53 is a cover plate extending over the operating mechanism, said bolt 45 extending therethrough and being provided with the securing nut 54 adapted to bear against such plate. The 30 plate is provided with a downwardly turned end 55 adapted to engage the upper knife 47.

40 The operation of the clipper mechanism is as follows:

By connecting the removable casing 7 to the depending portion 3 by means of the bayonet joints the wedge-shaped male member 6 is inserted into the member 17 and thus 45 forms a driving connection thereto. When the motor is turned on, the crank wheel 18 is revolved and the link 21 reciprocated. When this occurs the arm 49 is oscillated and as the foot 51 thereof is connected with 50 the removable knife 47, such knife is moved back and forth across the face of the fixed knife 40, thus moving the teeth 56 of the knife 47 across the teeth 57 of the knife 40 and effecting the clipping operation.

55 When it is desired to use the drying fan it is merely necessary to replace the removable casing attached to the clipper mechanism, by the removable casing attached to the fan casing, or where it is desired to use the vibrator it is only necessary to apply its casing to the motor.

The operation of the vibrator is as follows:

60 The eccentric foot 27 operating in the 65 socket 29 rocks the rod 28 back and forth

about the lower end 30 thereof, thus vibrating the sphere 33.

From the above description it will be seen that the barber in using the instrument will be able to change the attachments 70 with the greatest possible facility, simply by removing the particular casing 7 from the depending portion 3 by disconnecting the same at the bayonet joints. He can then use any other attachment he requires, 75 and consequently only one electric motor will be necessary to operate the three attachments instead of having to make use of a separate motor for each.

80 What I claim as my invention is:

1. In a device of the character described, the combination with an electric motor and the shaft thereof, of a casing detachably secured to the motor, a wedge-shaped male member secured to the lower end of the motor shaft, a stub shaft in the casing, a female member having a tapering interior mounted on the stub shaft, said stub shaft mounted in a suitable bearing in the casing, a crank wheel on the lower end of said stub shaft, 90 and means for driving the clipper mechanism from the crank wheel.

2. In a device of the character described, the combination with an electric motor and the shaft thereof, of a casing detachably secured to the motor, a wedge-shaped male member secured to the lower end of the motor shaft, a stub shaft in the casing, a female member having a tapering interior mounted on the stub shaft, said stub shaft mounted in a suitable bearing in the casing, a crank wheel on the lower end of said stub shaft, a 100 fixed clipper knife having suitable teeth suitably secured to the casing, a movable clipper knife having suitable teeth super-imposed above the aforesaid knife, 105 clipper mechanism attached to the casing, and means for driving the movable knife from the crank wheel for reciprocating the said knife laterally.

110 3. In a device of the character described, the combination with an electric motor and the shaft thereof, of a casing detachably secured to the motor, a wedge-shaped male member secured to the lower end of the motor shaft, a stub shaft in the casing, a female member having a tapering interior mounted on the stub shaft, said stub shaft mounted in a suitable bearing in the casing, a crank wheel on the lower end of said stub shaft, 115 a fixed clipper knife having suitable teeth suitably secured to the casing, a movable clipper knife having suitable teeth super-imposed above the aforesaid knife, clipper mechanism attached to the casing, and means for driving the movable knife from the crank wheel for reciprocating the said knife laterally, the upper knife having a notch at 120 its rear edge, an arm pivoted intermediately of its length, one end of the arm having a 125 130

turned down foot engaging the notch in the movable knife and the other end being turned upwardly, a crank pin on the crank wheel, and a driving link pivotally connected at one end to the crank pin and at the other end to the upwardly turned end of the said arm.

4. In a device of the character described, the combination with an electric motor and the shaft thereof, of a casing detachably secured to the motor, a wedge-shaped male member secured to the lower end of the motor shaft, a stub shaft in the casing, a female member having a tapering interior mounted on the stub shaft, said stub shaft mounted in a suitable bearing in the casing, a crank wheel on the lower end of said stub shaft, a fixed clipper knife having suitable teeth suitably secured to the casing, a movable clipper knife having suitable teeth superimposed above the aforesaid knife, clipper mechanism attached to the casing, and means for driving the movable knife from the crank wheel for reciprocating the said knife laterally, the upper knife having a notch at its rear edge, an arm pivoted intermediately of its length, one end of the arm having a turned down foot engaging the notch in the movable knife and the other end being turned upwardly, a crank pin on the crank wheel, a driving link pivotally connected at one end to the crank pin and at the other end to the upwardly turned end of the said arm, and a cover plate secured to the side of the casing, the lower end of said cover plate adapted to engage the upper face of the movable knife.

5. In a device of the character described, the combination with an electric motor and the shaft thereof, of a casing detachably secured to the motor, a plate suitably secured to the bottom of the casing, said casing having a side aperture therein, a fixed clipper knife having suitable teeth, said knife secured to the said plate, a movable clipper knife having suitable teeth, said knife superimposed above the fixed knife and having a notch in its rear face, a pivot pin extending up from the aforesaid plate, an arm having a downwardly turned end adapted to engage the notch in the movable clipper knife and an upwardly turned end, said pivot pin pivotally mounting said arm intermediately of its length, a crank pin on the crank wheel, and a driving link pivotally secured at one end to the crank pin and at the other end to the upwardly turned end of the arm.

6. In a device of the character described, the combination with an electric motor and the shaft thereof, of a casing detachably secured to the motor, a plate suitably secured to the bottom of the casing, said casing having a side aperture therein, a fixed clipper knife having suitable teeth, said knife se-

cured to the said plate, a movable clipper knife having suitable teeth, said knife superimposed above the fixed knife and having a notch in its rear face, a pivot pin extending up from the aforesaid plate, an arm having a downwardly turned end adapted to engage the notch in the movable clipper knife and an upwardly turned end, said pivot pin pivotally mounting said arm intermediately of its length, a crank pin on the crank wheel, a driving link pivotally secured at one end to the crank pin and at the other end to the upwardly turned end of the arm, and a cover plate secured at one end of the casing, said pivot pin extending through the said cover plate, a nut threaded on the upper end of the pivot pin and adapted to be threaded down thereon to engage the cover plate, the lower end of the cover plate engaging the upper surface of the movable clipper knife.

7. In a device of the character described, the combination with an electric motor and the shaft thereof, of a casing detachably secured to the motor, a plate suitably secured to the bottom of the casing, said casing having a side aperture therein, a fixed clipper knife having suitable teeth, said knife secured to the said plate, a movable clipper knife having suitable teeth, said knife superimposed above the fixed knife and having a notch in its rear face, a pivot pin extending up from the aforesaid plate, an arm having a downwardly turned end adapted to engage the notch in the movable clipper knife and an upwardly turned end, said pivot pin pivotally mounting said arm intermediately of its length, a crank pin on the crank wheel, a driving link pivotally secured at one end to the crank pin and at the other end to the upwardly turned end of the arm, and a cover plate secured at one end to the casing, said pivot pin extending through the said cover plate, a nut threaded on the upper end of the pivot pin and adapted to be threaded down thereon to engage the cover plate, the lower end of the cover plate engaging the upper surface of the movable clipper knife, the lower end of the pivot pin having an enlarged head, an indenture in the upper surface of the fixed clipper knife adapted to receive the enlarged head of the pivot pin.

8. In a device of the character described, the combination with an electric motor and the shaft thereof, of a detachable casing, a plate secured to the bottom of said casing, a fixed clipper knife secured to said plate, said clipper knife having suitable teeth, a movable clipper knife having suitable teeth, said movable clipper knife superimposed above the fixed clipper knife, the upper clipper knife having a notch in its rear edge, a pivot pin suitably secured to the plate, an arm freely mounted on the pivot pin, one

- end of said arm having a downwardly turned foot engaging the notch in the movable knife and the other end turned upwardly, and means for imparting an oscillatory driving motion to the said arm from the motor shaft.
9. In a device of the character described, the combination with an electric motor and the shaft thereof, of a clipper attachment, a vibrator attachment and a drier fan attachment, a casing for each attachment, means for detachably securing any one of the aforesaid casings to the motor for securing the particular attachment thereto, stub shafts, said stub shafts being journaled in the respective casings, a detachable driving connection between the motor shaft and each stub shaft, one portion of the driving connection being applied to the motor shaft and the other portion to each of the stub shafts and means for applying any particular attachment and casing to the motor whereby the stub shaft thereof and the attachment connected thereto is driven from the motor shaft.
10. In a device of the character described, the combination with an electric motor and the shaft thereof, of a clipper attachment, a vibrator attachment and a drier fan attachment, a casing for each attachment, means for detachably securing any one of the aforesaid casings to the motor for securing the particular attachment thereto, a wedge shaped male member on the lower end of the motor shaft, stub shafts, an interiorly tapered female member on the upper end of each of the stub shafts, said stub shafts being journaled in the respective casings, said male and female members forming a detachable driving connection between the motor shaft and each stub shaft and means for applying any particular attachment and casing to the motor whereby the stub shaft thereof and the attachment connected thereto is driven from the motor shaft.
11. In a device of the character described, the combination with an electric motor and the shaft thereof, of a casing detachably secured to the motor, a stub shaft in the casing, said stub shaft mounted in a suitable bearing in the casing, a detachable driving connection between the motor shaft and the stub shaft, a crank wheel on the lower end of said stub shaft, and means for driving the clipper mechanism from the crank wheel.
12. In a device of the character described, the combination with an electric motor and the shaft thereof, of a casing detachably secured to the motor, a stub shaft in the casing, said stub shaft mounted in a suitable bearing in the casing, a detachable driving connection between the motor shaft and the stub shaft, a crank wheel on the lower end of said stub shaft, a fixed clipper knife having suitable teeth suitably secured to the casing, a movable clipper knife having suitable teeth superimposed above the aforesaid knife, clipper mechanism attached to the casing, and means for driving the movable knife from the crank wheel for reciprocating the said knife laterally.
13. In a device of the character described, the combination with an electric motor and the shaft thereof, of a casing detachably secured to the motor, a stub shaft in the casing, said stub shaft mounted in a suitable bearing in the casing, a detachable driving connection between the motor shaft and the stub shaft, a crank wheel on the lower end of said stub shaft, a fixed clipper knife having suitable teeth suitably secured to the casing, a movable clipper knife having suitable teeth superimposed above the aforesaid knife, clipper mechanism attached to the casing, and means for driving the movable knife from the crank wheel for reciprocating the said knife laterally, the upper knife having a notch at its rear edge, an arm pivoted intermediately of its length, one end of the arm having a turned down foot engaging the notch in the movable knife and the other end being turned upwardly, a crank pin on the crank wheel, and a driving link pivotally connected at one end to the crank pin and at the other end to the upwardly turned end of the said arm.
14. In a device of the character described, the combination with an electric motor and the shaft thereof, of a casing detachably secured to the motor, a stub shaft in the casing, said stub shaft mounted in a suitable bearing in the casing, a detachable driving connection between the motor shaft and the stub shaft, a crank wheel on the lower end of said stub shaft, a fixed clipper knife having suitable teeth suitably secured to the casing, a movable clipper knife having suitable teeth superimposed above the aforesaid knife, clipper mechanism attached to the casing, and means for driving the movable knife from the crank wheel for reciprocating the said knife laterally, the upper knife having a notch at its rear edge, an arm pivoted intermediately of its length, one end of the arm having a turned down foot engaging the notch in the movable knife and the other end being turned upwardly, a crank pin on the crank wheel, a driving link pivotally connected at one end to the crank pin and at the other end to the upwardly turned end of the said arm, and a cover plate secured to the side of the casing, the lower end of said cover plate adapted to engage the upper face of the movable knife.

EDWARD DONALD CAMPBELL.
